HANDLE FOR A SPOON, FORK, OR SIMILAR ARTICLE

Morton Hepner, New York, N. Y.

Application October 24, 1951, Serial No. 17,092
Term of patent 3½ years

(Cl. D44—29)

To all whom it may concern:

Be it known that I, Morton Hepner, a citizen of the United States, residing at New York, in the county of New York and State of New York, have invented a new, original, and ornamental Design for a Handle for a Spoon, Fork, or Similar Article, of which the following is a specification, reference being had to the accompanying drawing, forming part thereof.

In the drawing:

Fig. 1 is a top plan view of a handle for a spoon, fork, or similar article, showing my new design;

Fig. 2 is a bottom plan view;

Fig. 3 is a side elevational view; and

Fig. 4 is an end view of the same.

The dominant features of the design reside in the portions shown in full lines.

I claim:

The ornamental design for a handle for a spoon, fork, or similar article, as shown and described.

MORTON HEPNER.
